TABLE AND CHAIR COMBINATION

Gerald G. Conklin, Rte. 1, Box 12,
St. Joseph, Mich. 49085

Filed Apr. 13, 1967, Ser. No. 6,672

Term of patent 14 years

(Cl. D33—14)

FIG. 1.

FIG. 2.

FIG. 4.

FIG. 3.

FIG. 1 is a front perspective view of a table and chair combination embodying the design;

FIG. 2 is a front perspective view similar to FIG. 1 but showing the chairs in their folded position, in which the seats are removed;

FIG. 3 is an overhead plan view of the table and chairs as seen in FIG. 1; and

FIG. 4 is a plan view of the table and chairs as seen in FIG. 2.

I claim:

The ornamental design for a table and chair combination, substantially as shown.
